Emil Kromer,

By Longfellow Attorney

UNITED STATES PATENT OFFICE.

EMIL KROMER, OF SPRINGFIELD, MISSOURI.

BORING-TOOL.

1,303,071.

Specification of Letters Patent.

Patented May 6, 1919.

Application filed July 26, 1918. Serial No. 246,918.

To all whom it may concern:

Be it known that I, EMIL KROMER, of Springfield, county of Greene, and State of Missouri, have invented certain new and useful Improvements in Boring-Tools, of which the following is a specification.

This invention relates to a boring bar adapted to bore the inside of cylinders and particularly air pumps and other multi-cylinder devices.

One of the objects of the invention is to provide a boring bar which may be utilized for boring the cylinders without the necessity of disassembling the parts.

Another object of the invention is to provide a sectional operating rod so that the length of the rod may be increased or diminished, as occasion may demand. It is also the purpose of the invention to provide an improved construction of boring head whereby a multiplicity of cutters may be simultaneously adjusted in the head so as to have uniform radial movements. It is also the purpose of the invention to provide a head in which a counter-boring tool may be applied if desired.

Other objects and advantages of the invention will be apparent hereinafter, it being understood that changes in the form, proportions and line details of construction may be resorted to without departing from the scope of the invention or sacrificing any of its advantages.

In the drawings,

Figure 1 is a vertical longitudinal sectional view through the cylinders of an air compressor showing the application of the invention.

Fig. 2 is a cross sectional view on the line 40 2-2 of Fig. 1.

Fig. 3 is an enlarged sectional view through the boring head.

Fig. 4 is an end view of the boring head.

Fig. 5 is a sectional view on the line 5-5 of Fig. 3.

Fig. 6 is a fragmentary detail view of the counter-boring tool; and

Fig. 7 is an enlarged fragmentary longitudinal sectional view illustrating the coupling for complementary sections of the operating rod.

Referring now to the drawings by numerals of reference, 1 and 2 designate tandem cylinders of an air compressed or simi-

lar machine, the cylinders of which are to be bored. The cylinders are shown as connected by head 3, and are provided with the usual packing glands 4 and 5. The boring tool is shown as consisting of a rod having a portion of its length indicated at 6 smooth, and preferably of a diameter substantially equal to that of the piston rod normally passing through the glands 4 and 5, so that the smooth portion 6 of the rod will serve the purpose of centering the head and the tools carried thereby. One end of the rod is threaded as at 7, the threaded portion being shown as of greater diameter than the portion 6, and on the threaded portion is positioned the head. In order that the chuck 70 may be held in its proper position, an abutment ring or shoulder 8 is threaded thereon, and against which the head 9, also threaded on the rod, is adapted to bear. The head 9 is provided with a plurality of radial slots 10 to receive the boring blades or tools 11, said tools being adapted to be initially adjusted by the split ring consisting of the members 12 and 13 and held in the recess 14 in the head 9. By reference to Fig. 3, it will be observed that the blades or tools 11 are provided with notches 15 adapted to fit over the outstanding flanges of the ring, the width of the notches being in excess of the thickness of the ring flange, so that the tools 11 may be moved radially in their slots. The tools are held in proper operative positions by means of a plate 16, having bolts or dowels 17 which project through the head 9 to receive the nuts 18. The central threaded opening 19 of the plate 17 is of greater diameter than the diameter of the portion 6 of the rod, and within said opening and snugly fitting the portion 6 of the rod is an exteriorly threaded expanding nut 20 having a beveled face 21 bearing against corresponding faces 22 on the inner ends of the tools 11, the recesses 23 permitting the application of a spanner for the purpose of screwing the nut in the opening 19. The head 9 is also provided with a recess 24 to receive a counter-boring tool 25 which may be fastened therein in any well known manner, so as to be readily movable when its use is not desired. In order to assist in affording stability to the rod when in use, I have provided a yoke 26 having inturned ends 27 and 28, adapted to be secured to one of the

- cylinders by the fastening devices 29 and 30. The yoke is provided with an opening 31 in line with the glands 4 and 5, and threaded thereon is a gland 32 which may be fastened 5 to the yoke by the fastening devices 33 and 34. The threaded portion of the rod may be made up of a number of sections. For example, that portion adjacent to the head may have a restricted extension 35 fitting in 10 a socket 36 of a complementary threaded member, and when the complementary member is applied the two may be coupled together by the transverse threaded pin 36 (see Fig. 7). 15 When the parts are assembled, as shown in Fig. 1, a drill press, motor or other actuating device may be coupled with the rod, so that its rotating part will cause a rotation of the boring head, and as the boring 20 takes place the head will be automatically fed along the inside of the cylinder by the threaded connection between the gland 32 and the threaded portion 7 of the rod, the glands 4, 5, and 32 causing the head to be 25 properly centered. When it is desired to bore an abnormally long cylinder, the threaded portion of the rod may be lengthened by adding a requisite number of complementary members. Under ordinary con-

ditions, however, these complementary members may not be used.

I claim:

1. In a cylinder boring device, a boring head having radial slots, a recessed ring in the head, radially adjustable blades in the slots and having notches receiving the ring, the width of the notches being in excess of the thickness of the ring, a plate for confining the blades in the slots, means for securing the plate to the head, and an expanding 35 nut threaded in the plate and having a beveled end bearing against the ends of the blades.

2. In a cylinder boring device, a boring head, a cover plate spaced from and secured rigidly thereto, a split ring in a recess in the head, notched blades radially disposed within the space between the plate and the head, the notches receiving the edge of the ring, and an expanding nut for imparting radial 40 movement to said blades.

The foregoing specification signed at Springfield, Missouri, this 16 day of April, 1908.

EMIL KROMER.

In presence of:

W. W. SHACKELFORD,

H. P. JOHN.

Copies of this patent may be obtained for five cents each, by addressing the "Commissioner of Patents,"

Washington, D. C.

Correction in Letters Patent No. 1,303,071.

It is hereby certified that in Letters Patent No. 1,303,071, granted May 6, 1919, upon the application of Emil Kromer, of Springfield, Missouri, for an improvement in "Boring-Tools," an error appears in the printed specification requiring correction as follows: Page 2, lines 53-54, date of execution, for "16 day of April 1908" read *16 day of April, 1918*; and that the said Letters Patent should be read with this correction therein that the same may conform to the record of the case in the Patent Office.

Signed and sealed this 17th day of June, A. D., 1919.

[SEAL.]

J. T. NEWTON,

Commissioner of Patents
